UNITED STATES PATENT OFFICE.

WILLIAM E. BORST AND CLARENCE C. GILLEO, OF GRAND RAPIDS, MICHIGAN.

APPARATUS FOR COOLING MOLDS OF TYPE-METAL-SLUG-CASTING MACHINES.

1,389,573.

Specification of Letters Patent. Patented Sept. 6, 1921.

Application filed September 15, 1919. Serial No. 324,009.

To all whom it may concern:

Be it known that we, WILLIAM E. BORST and CLARENCE C. GILLEO, citizens of the United States of America, residing at Grand Rapids, in the county of Kent and State of Michigan, have invented certain new and useful Improvements in Apparatus for Cooling Molds of Type-Metal-Slug-Casting Machines; and we do hereby declare the following to be a full, clear, and exact description of the invention, such as will enable others skilled in the art to which it appertains to make and use the same.

This invention relates to an apparatus for cooling the walls of mold cells of molds in type metal slug casting machines. The molten metal which is injected into the mold cells should, in order to produce a perfect type face, be heated considerably above the melting point of the metal so that it will flow freely and completely fill the interstices of the matrices and make perfect type characters. On the other hand it has heretofore been necessary to keep the temperature of the molten metal low in order that the under face of the type slugs cast into the machine shall be as substantial as possible, it being apparent that this under face of a type slug is the last to cool and solidify by reason of its being next to the metal mouth piece and at the rear side of the mold wheel so that its cooling by radiation is checked to a considerable degree. In practice, particularly with the thicker slugs, the molds, in a short time, become very hot and the rear under side of the slugs when ejected from the molds are usually more or less porous and are usually cast with a long irregular cavity or groove many times extending the full length and width of the slug and leaving only a very thin edge at each side of the slug to serve as a support therefor when it is put into a form. In many instances this cavity breaks through the side of the slug and at various points in the length of the slug there is no support or bearing for it when placed in the form. Moreover, the ejecting slide for the slugs enters this cavity in the rear side of the slug and its pressure against the metal which has partially solidified, causes the sides of the slugs to bend outwardly

making it wider at this side than in the remainder of its height whereby a poor and practically unserviceable slug for printing purposes is produced.

Our invention has for its object and purpose an apparatus for directly cooling the sides of mold cells against which the molten metal comes so that when the metal strikes the same it is instantly cooled and solidified, thus practically eliminating the pits and cavities in the under side of the slug and always leaving a substantial and solid side of the slug to serve as a base therefor when it is placed in the form. Our invention contemplates the passage of a current of air through the mold cell from the rear to the front thereof and in the provision of means for accomplishing this end. As a further step in the operation of cooling the mold the invention contemplates a shutting off of the passage of air during the time that the type slug is being ejected with an immediate rush of air through the mold cell as soon as the ejector slide is withdrawn. For an understanding of the invention, reference may be had to the following description taken in connection with the accompanying drawings, in which:

Figure 1 is a front view of a mold wheel illustrating the mold receiving openings therein, one of which is shown as filled with a mold and showing the position at which the slugs are ejected from the molds and the ejector slide guides back of the mold wheel.

Fig. 2 is a side view of the construction shown in Fig. 1.

Fig. 3 is a horizontal section taken substantially on the line 3—3 of Fig. 2.

Fig. 4 is a side elevation of a slug such as is ordinarily made in a machine without our invention.

Fig. 5 is an under plan view thereof; and

Fig. 6 is a view similar to Fig. 5 illustrating the under side of a slug made in a machine equipped with our invention.

Like reference characters refer to like parts in the different views of the drawings.

The mold wheel 1 with its four mold receiving openings 2 into which molds 3 may be placed and secured is of common and

well-known type such as is used in linotype machines. The mold 3 has a cell for receiving the molten metal as indicated at 4, the metal in molten form being projected into this cell from behind. The mold wheel turns to various positions so that the molds are at times placed directly in front of the mouth piece which passes the metal to the mold cells and then to the ejector mechanism for ejecting the slugs from the mold.

The ejecting mechanism in machines of this character comprises two vertical guide plates 5 and 6 having a slot 7 between them in which the ejector slide 8 is mounted, the same being moved forward at proper intervals to pass into the mold cells 4 and force the slug therefrom. The mechanism for operating the ejector slide is no part of the present invention and is not illustrated in any way, being well-known to those skilled in the art relating to linotype machines.

A pipe 9 is located alongside one of the guide plates, such as 6, and reaches nearly to the front end thereof, being then provided with a bend 10 which is fastened to said plate 6 passing therethrough so that free communication to the slot 7 is made. The usual position of the ejector plate 8 is such that its front end lies just back of the point where the bend 10 passes through the plate 6. It is apparent that with the pipe 9 leading to any suitable reservoir containing compressed air, whenever a mold is moved so that its cell comes directly in front of the ejector mechanism, a continuous current of air is blown through the cell from the rear to the front. There is only one time when this passage of air is interrupted. When the mold wheel is turned with the mold carrying a slug to position in front of the ejector mechanism and the ejector slide 8 is moved forward during the operation of forcing the slug from the cell 4, the end of the bend at 10 is covered and no air passes, but as soon as the slide 8 moves back to its normal position there is a quick rush of air which passes through the mold cell with a consequent quick initial cooling of the walls of the cell. The air continues to pass through the cell as long as the mold wheel remains in that position and the walls of the cell are rapidly cooled so that when this mold is again moved to the metal mouth piece and molten metal forced into its cell, the metal coming against the walls of the cell is immediately cooled and solidified, particularly at the rear portions of the walls of the cell as this is where the air first strikes and cools the same.

In Figs. 4 and 5 a representation is made of the way slugs made without this method look. The slugs 11 in their under sides having irregular grooves 12 of considerable depth which are not only nearly as wide as the slugs at all points in the length thereof but many times break through to make ir-

regular and ragged openings at 14 at the edges of the grooves and in any case the metal left is very thin and has too little strength to sustain the pressure against the upper side of the slug when it is placed in a form and used in printing. Moreover, it is apparent that as the ejector slide 8 moves forward to push a slug of this character from the mold cell its front edge will enter the groove at 12 and have a tendency to force the adjacent sides of the slug outwardly making it wider at the bottom than it should be so that it does not fill well into the form and is not held securely by its engagement with the sides of the adjacent slugs. With our invention the slug produced is like that shown in under plan view in Fig. 6. The groove 12a is narrow and is of much less depth than the groove at 12 shown in Fig. 5, while at each side of the groove solid bearing surfaces 15 are made which support the slug in the form when used in printing and there is no possibility of an outward wedging or bending on account of the insertion of the front end of the ejector slide 8 in the groove.

This invention has proven especially serviceable in actual practice. While very simple so far as constructive features are concerned it is very efficient to cool the molds particularly the walls of the mold cell and permit a higher temperature for the type metal which will insure that the type face of every slug is perfect while the opposite under face of the slug is at all times of more than sufficient width to make a secure and solid support for the slugs in the printing form.

We claim:

1. An apparatus comprising a mold wheel adapted to carry a mold, an ejector guide back of the mold and having a passage adapted to align with the opening in the mold, and means for carrying compressed air to said passage in said guide, substantially as and for the purposes described.

2. In a linotype machine including a mold wheel adapted to carry a mold having a slug casting opening therethrough and an ejector guide mounted back of the mold wheel having a passage therethrough adapted to align with the opening in the mold, of a pipe connected with the ejector guide and communicating with the passage therein, said pipe being adapted to carry compressed air to said passage for passage therefrom through the opening in the mold, substantially as described.

3. An apparatus comprising a mold wheel adapted to carry a mold, an ejector guide back of the mold, an ejector slide carried in the guide adapted to pass through the mold cell, and a pipe adapted to carry compressed air connected to the guide at a point in front of the normal position of the slide therein,

to thereby carry compressed air into the guide and through the mold cell, substantially as described.

4. An apparatus comprising a mold wheel adapted to carry a mold, an ejector guide back of the mold, an ejector slide carried in the guide adapted to pass through the mold cell, and means for carrying compressed air

into the ejector guide in front of the normal position of said ejector slide, substantially as 10 and for the purposes described.

In testimony whereof we affix our signatures.

WILLIAM E. BORST.
CLARENCE C. GILLEO.
